FIG. 6.

UNITED STATES PATENT OFFICE.

ELIAS E. RIES, OF NEW YORK, N. Y.

MEANS FOR REMOVING SLEET, &c., FROM ELECTRICAL CONDUCTORS.

SPECIFICATION forming part of Letters Patent No. 743,331, dated November 3, 1903.

Application filed September 4, 1903. Serial No. 171,886. (No model.)

To all whom it may concern:

Be it known that I, ELIAS E. RIES, a citizen of the United States, and a resident of New York, in the county of New York and State of New York, have invented certain new and useful Means for Removing Sleet, &c., from Electrical Conductors, of which the following is a specification.

My invention has for its object the removal of sleet, snow, ice, &c., from railway-tracks, more particularly from the contact-rails or supply-conductors that are usually employed on electric railways for supplying energy to the motors on the cars or trains traveling thereon. Such contact-rails or supply-conductors are ordinarily located overhead in the form of trolley-wires, or underground in the case of underground-conduit electric railways, or they are located along the road-bed itself either between or at one or both sides of the track-rails, as in the case of third-rail electric-railway systems, whether the same be located on the surface or on elevated structures. In all such cases these contact or supply conductors being necessarily naked or un-insulated in order to permit of electrical contact being made therewith by the trolleys, shoes, brushes, or other current-collecting devices with which the motor cars or trains are equipped are more or less exposed to the elements.

In the winter season it has been found in the operation of overhead-trolley, underground-conduit, and third-rail electric railways that the exposed contact-surfaces of the supply-conductors when subjected to moisture at times when the surrounding atmosphere is even a few degrees below the freezing-point would cause a condensation of such moisture thereon in the form of sleet, which interferes with the proper operation of the system. It is also found that after a fall of rain, hail, or snow the moisture necessarily deposited upon the exposed line conductors would freeze and incase the same with a crust of ice and dependent icicles, which prevent electrical contact of the shoes or other current-collectors with the supply-conductors, since such coating acts not only as a fairly good insulator, but also serves to prevent mechanical contact of the collecting-shoes with the contact-rails, thus seriously inter-

ferring with the running of cars and in many cases tying up all traffic on the road.

It is my aim to maintain the efficiency of an electric system, and particularly of an electric-railway system, by preventing the accumulation on such an exposed conductor of ice, sleet, snow, &c., or by removing the same after a partial accumulation of such substance. I accomplish this result by heating the exposed conductor to a suitable temperature for melting and evaporating any rain, ice, snow, &c., which may fall or accumulate on the conductor. The desired elevation of temperature is obtained by passing through such conductor a suitable electric current. Any electrical system capable of raising the temperature of such an exposed conductor to the desired point at any hour of day or night without interfering with the transmission of the regular electric current—such, for example, as the usual-motive or working current for propelling cars on a line of railway—should be so organized as to remove translating devices or motors fed by the regular current from the influence of current designed to heat the exposed conductor.

The principal feature of my invention, therefore, is the provision of two paths or circuits for current flowing in the system, one of these paths being the regular circuit through which the working current flows, while the other path is a circuit through which a current of different character is passed, this current being preferably of large heating capacity, usually an alternating current of low potential and large volume or amperage. As the exposed conductor forms part of the regular or working circuit, it will be evident that in order to be heated up by another current of different character it should also form part of the circuit through which such heating-current flows, and in my present system the two principal electric circuits have a common conductor formed by the exposed conductor or third rail of the system, this exposed conductor usually constituting one side of each circuit and permitting the simultaneous transmission therethrough of two currents of entirely different characters, one of which is the regular or working current for supplying the translating devices or motors of the system, while the other is a current of entirely differ-

ent character capable of heating the exposed conductor to the proper point for preventing or removing accumulations of sleet, snow, &c., without in any way interfering with the 5 transmission of the main electric current or with the proper operation of the translating devices supplied by such current.

In applying my invention to an electric-railway system I have found that it is feasible to eliminate the traffic-rails as a factor 10 from the heating-circuit, since these can be kept sufficiently cleared from deposits of sleet, ice, and snow by the regular traffic over the line, assisted in the case of a heavy fall of 15 snow by the ordinary mechanical appliances now generally used for clearing the road-bed of such accumulations. In accordance with my present invention, therefore, I utilize only the contact-rails in my heating circuit or 20 circuits, and I do this in such a manner as will permit of the transmission of the low-tension heating-currents preferably employed by me over the same without in any wise interfering with the simultaneous transmission 25 through the same of the regular propelling-currents that are fed by said contact-conductors into the motor-circuits and are thence returned through the traffic-rails. I am furthermore enabled by my invention to produce 30 the necessary heating-currents with, comparatively speaking, a very small fraction of the total electrical energy that would be otherwise required. This latter feature, as will hereinafter more fully appear, I accomplish 35 by cross-connecting the two supply-conductors or contact-rails of, say, a double-track road at certain intervals, and thus subdividing the same into local heating-circuits of comparatively short lengths or sections. 40 In order to still further reduce the consumption of electrical energy—that is to say, in order to prevent the placing of too great a load upon the generators at the power station or stations of the line—I preferably provide 45 means, as will subsequently appear, for heating different sections or groups of sections successively instead of simultaneously. I also provide other novel features of construction and arrangement, as well as operation, 50 by means of which additional advantages and economies are gained and whereby my improved system may be readily and economically installed.

In the drawings accompanying this specification, and forming part of the present application, Figure 1 is a diagrammatic view illustrating three simple combinations of electrical devices for supplying a working current and a heating-current separately or simultaneously to a main circuit and a heating-circuit having a common conductor. Fig. 2 is a similar diagrammatic view illustrating the division of the rails of a third-rail system into sections of different widths, any one of 65 which sections may be heated independently of the others. Fig. 3 is a side elevation of a portion of a third-rail system, illustrating a

train having on the car a traveling heating-circuit one side of which is a portion of the third rail included in the working circuit. 70 Fig. 4 is a diagrammatic view similar to Fig. 1, illustrating a preferred construction for heating an exposed conductor or third rail, the entire heating-circuit in this view being divided into a plurality of sections each of 75 which has a separate source of current for economically heating the different sections. Fig. 5 is a plan of a modification of my invention, illustrating the manner in which three third rails may be connected and heated 80 current supplied thereto. Fig. 6 is a diagrammatic view illustrating third rails divided into sections heated by transformers connected in parallel and arranged in groups adapted to be energized separately. Fig. 7 85 is a detail illustrating diagrammatically means for supplying polyphase currents for heating exposed conductors. Fig. 8 is a detail illustrating automatic means for controlling the supply of the heating-current. Fig. 90 9 is a detail illustrating a switch and a counter-electromotive-force device for controlling the current supplied to a heating-transformer. Fig. 10 is a cross-sectional detail of the traffic-rails and third rail of a third-rail system. 95 Fig. 11 is a detail illustrating a current-collecting shoe for making contact with the third rail.

Similar characters designate like parts in all the figures of the drawings. 100

My invention may be embodied in any electrical system in which it is desired to heat one of the conductors of an electric circuit, whether for the purpose of removing a light coating of dew, rain, sleet, or snow or a heavier coating of ice, &c., and it may be applied to any system in which such conductor is exposed to the elements, although its principal use will be found to be in connection with the exposed or working conductors of an 105 electric-railway system. It is peculiarly adapted for use in third-rail systems, because of the great surface exposed to the elements by such a conductor and the consequent necessity for removing such a non-conducting and 110 contact-preventing medium as sleet or thick ice from the exposed working conductor. 115

In the case of a single-track system the third rail will of course be connected in a suitable heating-circuit, while at the same time constituting part of the regular working circuit; but as it is usual in third-rail installations to provide two or more tracks with corresponding working conductors or third rails I prefer to form a heating-circuit common to both 120 tracks by connecting the third rails of the two tracks by cross-conductors and to provide at a point or or close to the track structure or line of way means for supplying a suitable electric current directly to the heating-circuit. 125 130

In Fig. 1 I have illustrated a simple type of electrical system for supplying a working or motive current to the main circuit and for supplying, preferably simultaneously there-

with, a current of different character, preferably of low potential, high amperage, and large heating capacity to an auxiliary or heating circuit. In this view 2 designates a source 5 of energy for supplying single or polyphase alternating current, this being the primary current on many electric railways, and 3 and 4 designate the usual mains or feed-wires. Three substations are also shown as supplied 10 with power from the main power-station, and at these substations suitable electrical apparatus is employed for supplying the different sections of the road with the working current and for also supplying heating-current to the exposed working conductors or third rails. The two tracks shown are designated by 5 and 6, respectively, and the third rails corresponding thereto are indicated at 7 and 8. In the construction shown in this view these 15 third rails are divided into sections of any desired length—say about two thousand feet—each section of the road preferably having the opposite third rails thereof directly connected at at least one end thereof by a heavy cross-conductor, such as the cable 9. In Fig. 1 the ends of these sections opposite the cross-conductor 9 are connected in various ways to indicate the different means which may be readily used with existing types of third-rail 20 systems. In the first section of this view the system is so organized that the same source of energy may supply the working current to the motive circuit and also the heating-current to the auxiliary or heating circuit. In 25 this embodiment, however, which is intended to illustrate merely an emergency application of my invention, the current is turned off from the working circuit when it is desired to pass current through the heating-circuit. 30 This current is the usual direct or continuous current, delivered by a substation rotary converter 10, connected to the feed-wires 3 and 4, fed by the alternating-current generator 2. The wires 11 and 12, leading from 35 this converter, pass to the two-way switch 13, the arms of which coöperate with three terminals, to which are connected three heavy bus-wires 14, 15, and 16, the first of which is connected to a cross-conductor or cable 17 for 40 bonding the ends of the wires of the two tracks nearest the substation, while the bus-wires 15 and 16 are connected directly to the third rails 7 and 8 of the first section. According 45 to the positions of the switch 13, as indicated in dotted and full lines, current is passed either through the two working circuits, which include the track-rails, or through an auxiliary heating-circuit only, which includes the third rails of the working circuits, but excludes 50 the track-rails thereof and the motors on the vehicles controlled by such working current.

In the second section (shown in Fig. 1) a substation rotary converter 18 is connected 55 to the feed-wires 3 and 4 by means of conductors 19 and 20, and the heavy conductors 21 and 22 of the secondary circuit are con-

nected, respectively, to the track-rails 5 and to the second section of the third rail 8, continuous current of relatively high tension being supplied by this converter to the working circuits of the second section of the system. In this second section the heating effect is not obtained by passing the whole of the direct current from the substation directly through the heating-circuit to the exclusion of the track-rails of the working circuit, as is done in the first section, but results from the use of a rotary converter, which transforms a portion of the alternating line-current into a direct current of lower potential, high amperage, and large heating capacity and feeds such low-tension current directly into the heating-circuit to the exclusion of the track-rails of the working circuit. 70 The primary of this rotary converter, which is designated by 23, is connected by suitable conductors to the main working circuit, connection being made herein to the conductors 19 and 20, and the secondary of the converter 75 is connected by heavy conductors or bus-wires 24 and 25 to the second sections of the third rails 7 and 8, at the ends thereof opposite the cross-conductor or bond-cable 9. The switch 26 is preferably placed in the main 80 circuit to said converter in order that current may be turned off from the converter, except at such times as it may be necessary to heat up the rails 7 and 8 to prevent or remove accumulation of sleet or other substance thereon. This mode of heating the working conductors or third rails is preferable to that shown in the first section, as it is more economical and does not involve the turning off 85 of the current from the working circuit or 90 circuits.

In the third section of Fig. 1 a substation-converter 27 is connected to the mains 3 and 4 by conductors 28 and 29 and is connected in the working circuit of the third section in 95 the same manner as the substation-converter 18. The heating-current in this case, however, is obtained from a static transformer 30, the primary of which is connected to the main supply-circuit and is controlled by a 100 switch 31, while the secondary of the transformer is connected to the third rails 7 and 8 at the beginning of the third section by conductors 32 and 33. The efficiency of this 105 mode of heating the third rails is approximately the same as that of the second section.

It is desirable to subdivide the heating-current in all cases in order that the necessary heating effect may be obtained without making too sudden and heavy a demand on the 110 source of energy. This subdivision may be made in various ways, one of which is illustrated in Fig. 2. Here the track-rails are designated by 5' and the working conductor or third rail by 7'. At different points in the 115 lengths of the track-rails and the third rail conductors, such as 35, 36, and 37 and 38, 39, and 40, are connected thereto. A source of direct 120 current, such as the generator 2', is connected 125 to the feed-wires 3 and 4 by means of conductors 19 and 20, and the heavy conductors 21 and 22 of the secondary circuit are connected 130 to the track-rails 5' and the third rail 7'.

to bus-bars 41 and 42, the conductors 35, 36, and 37 being connected to the former of these bus-bars, while a conductor 43 may connect the end of the third rail 7' nearest the generator with the bus-bar 42 through a normally open switch 44, which may be closed when it is desired to permit the passage of the current through the third rail for heating it. The feeders 38, 39, and 40 are all normally connected in circuit with the bus-bar 42 through switches 45, 46, and 47. When it is desired to pass a heating-current through the third rail 7', the switch 44 is closed and the switches 45, 46, and 47 are all opened, thereby compelling the entire return-current to pass through the third rail and heat the same without passing through the feeders 38, 39, and 40. When this is to be done, the generator 2' may be speeded up to compensate for the drop in potential due to the resistance of the long third rail. Traveling connection with the third rail is made through the usual current-collector or shoe 50, with one or more of which shoes each motor-car is customarily provided.

In Fig. 3 I have illustrated a modification of my invention in which the track-rails are designated by 5" and the working conductor or third rail by 7". In this view the auxiliary or heating circuit instead of being a fixed section or block of the whole system is a traveling circuit, which is carried on and moves with the vehicle or train which is propelled by the working current. For the purpose of converting the high-tension direct current of the working circuit into a current suitable for use in the heating-circuit a rotary converter, such as 23", is placed on the vehicle and connected to receive current from the working circuit through the current-collector or shoe 50' in the usual manner. A short local or heating circuit may be formed by connecting the secondary of this converter in circuit with said shoe and with another shoe at the rear of the car or train, such as the shoe 50", from which a conductor 51 passes to the other terminal of the secondary of the converter, the shoe 50' being in circuit with one of said terminals. A part of this local traveling heating-circuit is of course common to the main working circuit, as in the systems previously described, and a very economical heating of the third rail is possible with this apparatus, as by its use the length of the conductor to be heated at any one time is reduced to a minimum. This short heating-circuit may be used to advantage on pilot or construction trains. For nearly all purposes, however, I prefer to heat the exposed conductor or third rail substantially in the manner illustrated in Figs. 4, 5, and 6, in which three variations of the same general system are shown. In Fig. 4, 5" and 6" designate the down-track and up-track of a two-track third-rail system, and 7" and 8" represent the corresponding third rails. These third rails are preferably connected throughout, so

that each forms a continuous conductor, and the two third rails are cross-bonded, as by means of heavy cables 9", at suitable intervals. These intervals need not necessarily be equal, and their lengths may be determined by the general nature of the system at a given point or on a given section, sections close to stations or containing upgrades, curves, or switches being preferably shorter than those on level stretches of the road in order that the exposed conductor of such sections may be cleared quickly by the higher degree of heat automatically developed in these sections. In the construction shown in Fig. 4 the working circuit is supplied with direct current from a substation rotary converter 10", which is fed with alternating current from an alternating generator 52 through feed-wires 53 and 54. The secondary of this rotary converter is connected by means of conductor 55 to the rails 5" and 6" of the two tracks and by means of conductor 56 to the cross bond or cable 9", that connects the two third rails 7" and 8". At the ends thereof shown in the drawings the system has a closed track-circuit through the heavy bond-wire 17". It will be observed that by this arrangement all the track-rails are bonded or connected together, so as to form one side of the working or railway circuit, while all the third rails of the system are likewise electrically connected together, so as to form the other side of the working circuit, as is now the usual practice in third-rail systems. The alternating current transmitted over the mains or feed-wires 53 and 54 is of high potential and in the working circuit of the railway system is transformed by the rotary converter 10" into a direct current also having a relatively high potential. In the heating-circuit, however, this alternating current is transformed into an alternating current of lower potential and high amperage having great heating capacity by means of step-down static transformers, such as 30", of any suitable type, the primaries of these transformers being connected, as by means of conductors 57 and 58, to the feed-wires or mains 53 and 54, while the secondaries are connected directly to the exposed conductors or third rails 7" and 8". One of the most important features of my system with respect to economy of operation is the mode of supplying heating-current to the heating-circuit, including the third rails. This I prefer to accomplish by feeding directly into such exposed conductors a transformed current of low potential and large heating capacity at such points in the system as will result in a minimum drop of potential owing to the relatively low resistance of each branch of the heating-circuit. Preferably each closed circuit formed by sections of the third rails 7" and 8", connected by cross-bonds 9", is divided into at least two parallel branches in order to reduce the resistance, and the heating-current is fed directly into each branch—as, for example,

by means of transformers (shown in Fig. 4) which are located at approximately the centers of each section or block of the heating-circuit. The courses followed by the two branches of the current flowing from and to the secondary of each of these transformers are indicated clearly by the arrows in Fig. 4. In most cases the length of each section or block of the heating-circuit may be, say, two thousand feet on straight and level sections, so that each of the branch circuits fed by their common transformer will be about a thousand feet in length ordinarily, which will result in a great saving as compared with such a section of the heating circuit fed from one end thereof and not subdivided into parallel branches. When the sections or blocks of the heating-circuit are made shorter than this—say one-half or one-fourth the length of the ordinary section, as will preferably be the case on up-grades, at starting-points, &c., for reasons that will hereinafter appear—it is apparent that the heating effect will be produced much more quickly than on a long section. The extent to which it is necessary to heat these exposed conductors or third rails depends chiefly upon the temperature of the surrounding atmosphere; but ordinarily it will not be necessary to raise the temperature of these conductors more than 10° Fahrenheit, as sleet and ice are the principal substances to be removed from the exposed conductors, and these ordinarily form when the temperature is but a few degrees below the freezing-point. A temperature elevation of about 6° Fahrenheit will usually be sufficient, and this temperature elevation can be obtained by the expenditure of about thirty-five-horse power of electrical energy per minute for a block containing four thousand feet of the ordinary third rail, which weighs approximately one hundred pounds per yard and has a cross-sectional area of about 9.8 square inches, with a conductivity approximately one-seventh of that of a bar of copper of equal area, and can be maintained by about one-sixtieth part of the energy required to produce such an initial rise in temperature owing to the capacity of the rail for storing or retaining the heat produced therein.

The greatest economy and the greatest practicable distribution of the extra load on the generator result from the use of such a system as that illustrated in Fig. 4, with the lengths of the sections properly proportioned to the gradients, starting-points, &c., and from the application of heating-current to such sections separately or successively in such a manner with regard to the degree of elevation of temperature developed therein as to heat up the more important short sections first and in a relatively short time and the longer sections afterward somewhat more slowly, and such currents may with advantage be applied intermittently or in regular succession instead of continuously to the several sections, so as to still further reduce

or distribute the load on the power-station. It will be evident that by this method and by the proper utilization of the heat-storage capacity of the third rails themselves the extra or emergency current consumed in the heating-circuit is distributed over a longer time interval in that it is only used for short periods of time on each section and that the sum of these periods represents not only a moderate expenditure of energy, but the requisite power for removing the sleet, &c., is developed without imposing too great or sudden a load on the generating or transforming station, as might be the case if it were attempted to clear the entire line simultaneously and within a brief interval of time—a procedure that I have found is as unnecessary as it is uneconomical.

In Fig. 5 I have illustrated a modification of the invention adapted for use in connection with three main circuits or track-circuits, the exposed conductors or third rails only being shown, together with means for supplying current thereto, as in other respects the system is substantially the same as that shown in Fig. 4. In this view, Fig. 5, the third rails 7^a and 8^a of the down-track and the up-track have between them a third rail 60, which is the working conductor of the circuit for a center track, such as is ordinarily used for express-trains on an elevated or underground third-rail system. These third rails are connected by cross-bonds 9^a to form two closed parallel heating-circuits divided into corresponding closed sections. Current may be supplied to these sections in any suitable way before described; but preferably a transformed alternating current of low potential, high amperage, and large heating capacity is supplied to the various sections, the different branches of each section either having separate transformers connected directly in each branch, as at 30^a, or a single transformer having a divided secondary being connected at the terminals of the secondary to the two outer rails and divided at the center of the secondary for connection to the center rail 60 to divide the current translated by the secondary between the two branches of the section.

In Fig. 6 I have illustrated another modification in which the heating-circuit is divided into sections by the cross-bonds 9^c, which sections are fed with heating-current by transformers 30^c similar to those shown in Figs. 4 and 5. The primaries of these transformers instead of being connected in a single circuit are connected in groups in parallel in different circuits, any one of which may be closed as desired, while the others remain open. In this view one wire 61 of each primary is connected to a common conductor 62, while the other wires of the primaries are connected in pairs or groups to different conductors, the conductors 63 being connected to the conductor 64, the conductors 65 to the conductor 66, and the conductors 67 to the conductor

63, each group being in parallel to reduce the resistance, and each of the conductors 64, 66, and 68 being separately connectible in circuit with the source of energy, such as 5 the alternating generator 52^d, by means of a switch 70, movable onto any one of the contacts 71, 72, 73, and 74 as may be desired. I regard this method of connecting sections in circuit separately as the most economical, 10 because not only is the resistance of each section reduced to the minimum by the proper proportioning of the length of each section in accordance with the grade and other conditions and by the division of each section into 15 two parallel branches of equal resistance fed by a divided heating-circuit, but the extra load on the generator is kept down as much as possible by heating different groups of sections of the road at different times, and 20 thus distributing the extra demand for energy over a considerable period of time. To remove a thick coating of ice or other substance quickly, an alternating heating-current of relatively high frequency may be employed, 25 the "skin effect" of which will cause the surface of the rail to be heated first, which will result in the removal of practically all such coating before the body of the rail is heated up to any considerable extent.

30 In Fig. 7 I have illustrated at 75 a poly-phase-generator of the "star" type having separate switches 76, 77, and 78 for three conductors 79, 80, and 81 leading therefrom, over which the currents of different phase may be 35 transmitted for heating different exposed conductors or third rails.

In Fig. 8 I have illustrated how the primary of a heating-transformer, such as 30^d, may be automatically connected in circuit with 40 an alternating generator, such as 52^d, by means of an automatic switch 82, operated in this case by a solenoid-magnet 83, controlled in any suitable manner and from any desired point.

45 In Fig. 9 I have illustrated how the current from an alternating generator, such as 52^e, may be passed either in series or divided and passed in parallel through the divided primary of a transformer, such as 30^e, having a 50 switch 84 for changing the connections of the primary sections 85 and 86 of the transformer from series to parallel, or vice versa, an inductive resistance 87 being also connected in circuit with said switch and the 55 primary of the transformer. This arrangement of divided primary winding for the transformers is useful in places where it is desirable in emergencies to produce a more rapid clearing of the third-rail section (by 60 connecting the primary coils in parallel) than would be effected by the normal or "series" connection alone. It may also be employed for rapidly elevating the rail to the requisite initial temperature, after which the radiation 65 losses may be taken care of and the rail maintained at the desired temperature by restoring the series connection. It will be observed

that the heavier secondary windings of the transformer are permanently connected across the third-rail sections, as I find this to be an 70 advantage even in seasons when the heating current or currents are not likely to be used, as in summer, &c.

The third rail of each track may of course be of any suitable construction and located 75 in any well-known manner either at the side of the track or between the track-rails, as illustrated in Fig. 10. It will also be obvious that my invention may be applied equally well for the removal of sleet, &c., from overhead wires and for the purpose of evaporating moisture from, and thus improving the insulation of, exposed conductors whether the same be used for electric-railway or other purposes.

85 Although the problem of removing ice, snow, &c., from exposed conductors, such as those of a third-rail system, may appear at first sight to call for the expenditure of such an amount of electrical energy as to interfere with the proper operation of the system, it will be evident that when such removal is made in the manner described herein there will never be any abnormal load on the power-house due to the use of an abnormal amount 95 of current for heating purposes, because by dividing the system into sections of different lengths, heating those sections in the order of their importance either separately or in groups, varying the period during which the 10 heating-current is turned into the rails of a section, according as it is more or less important to clean that section quickly or thoroughly, and by utilizing the heat-storage capacity of the rails, which admits of a rapid 105 heating of the section in a very short time and a gradual radiation of the heat stored, which radiation will extend over a comparatively long period of time, my improved system may be employed with the expenditure 110 of a very small percentage of additional energy over that required for traction purposes and without materially increasing the load on the power-house.

115 What I claim is—

1. The combination with a pair of electric circuits having a common conductor, of means for supplying to said circuits electric currents of different characters one of which currents is of large heating capacity.

120 2. In an electric-railway system, the combination with a pair of electric circuits having a common third rail exposed to the elements, of means for supplying to said circuits electric currents of different characters one of which currents is of large heating capacity for heating 125 said third rail.

3. In an electric-railway system, the combination with a pair of electric circuits having a common conductor, of means for supplying to one of said circuits a motive electric current of high potential and to the other of said circuits a heating-current of low potential, and an electric motor in traveling electrical con-

- connection with said common conductor and controlled by said motive current and unresponsible to said heating-current.
4. The combination with a pair of electric circuits having a common conductor, of means for simultaneously supplying to said circuits electric currents of different characters one of which currents is of large heating capacity.
5. The combination with a pair of electric circuits having a common conductor, of means for supplying to said circuits electric currents of different characters one of which is an alternating current of low potential and high amperage and large heating capacity.
- 15 6. The combination with a pair of electric circuits having a common conductor, of means for simultaneously supplying to said circuits electric currents of different characters one of which is an alternating current of low potential and high amperage and large heating capacity.
- 25 7. The combination with a pair of electric circuits having a common conductor, of means for supplying to one of said circuits a continuous electric current of high potential and to the other of said circuits an alternating current of low potential.
- 30 8. The combination with a pair of electric circuits having a common conductor, of means for supplying to one of said circuits a continuous electric current of high potential and to the other of said circuits an alternating current of low potential and high amperage and large heating capacity.
- 35 9. The combination with a pair of electric circuits having a common conductor, of translating devices connected in parallel in one of said circuits and in traveling electrical connection with said common conductor, and means for supplying to the circuit containing said translating devices an electric current capable of translation by said devices and to the other of said circuits a current of different character.
- 45 10. The combination with a pair of electric circuits having a common conductor and with translating devices connected in parallel in one of said circuits, of means for supplying to the circuit containing said translating devices an electric current capable of translation by said devices and to the other of said circuits a different current of large heating capacity.
- 55 11. The combination with a pair of electric circuits having a common conductor, of translating devices connected in parallel in one of said circuits and in traveling electrical connection with said common conductor, and means for supplying to the circuit containing the translating devices an electric current capable of translation by said devices and to the other of said circuits a different current of large heating capacity.
- 60 12. The combination with a pair of electric circuits having a common conductor, of translating devices connected in parallel in one of said circuits and in traveling electrical connection with said common conductor, and

- means for supplying to the circuit containing said translating devices an electric current capable of translation by said devices and for simultaneously supplying to the other of said circuits a different current of large heating capacity.
- 70 13. The combination with a pair of electric circuits one of which is relatively short as compared with the other and has a conductor common to the other, of means for supplying to said circuits electric currents of different characters.
- 80 14. The combination with a pair of electric circuits one of which is relatively short as compared with the other and has a conductor common to the other, of means for supplying to said circuits electric currents of different characters the current supplied to the shorter of said circuits being of large heating capacity.
- 90 15. The combination with a main electric circuit, of a plurality of auxiliary electric circuits each shorter than said main circuit and each having a conductor common to a portion of the main circuit, means for supplying electric current to said main circuit, and means for supplying to said auxiliary circuits electric current of a different character from that supplied to the main circuit.
- 95 16. The combination with a main electric circuit, of a plurality of auxiliary electric circuits each shorter than said main circuit and each having a conductor common to a portion of the main circuit, means for supplying electric current to said main circuit, and means for supplying to at least one of said auxiliary circuits simultaneously with the supply of the main current an electric current of different character and large heating capacity.
- 100 17. The combination with a main electric circuit, of a plurality of auxiliary electric circuits each shorter than said main circuit and each having a conductor common to a portion of the main circuit, means for supplying electric current to said main circuit, and means for supplying to said auxiliary circuits separately but simultaneously with the supply of the main current electric current of different character from the main current and of large heating capacity.
- 105 18. The combination with a main electric circuit, of a second circuit divided into a series of successive auxiliary or block circuits each of which has a conductor common to a portion of the main circuit, means for supplying electric current to said main circuit, and means for supplying to said auxiliary circuits electric current of a different character from that supplied to the main circuit.
- 110 19. The combination with a main electric circuit, of a second circuit divided into a series of successive auxiliary or block circuits each of which has a conductor common to a portion of the main circuit, means for supplying electric current to said main circuit, and means for supplying to said auxiliary circuits in any desired order but simultaneously with the supply of the main current

electric current of a different character from the main current and of large heating capacity.

20. The combination with a pair of electric circuits having a common conductor, of means for supplying electric current to one of said circuits, and a converter for supplying to said other circuit a different current of large heating capacity.

21. The combination with a pair of electric circuits having a common conductor, of means for supplying a continuous electric current to one of said circuits, and a rotary converter controlled by said continuous current adapted to supply to said other circuit a low-potential alternating current of large heating capacity.

22. The combination with a main electric circuit, of a plurality of auxiliary electric circuits each shorter than said main circuit and each having a conductor common to a portion of the main circuit, means for supplying electric current to said main circuit, and converters connected in said auxiliary circuits for supplying thereto electric current of a different character from that supplied to the main circuit.

23. The combination with a pair of electric circuits having a common conductor, of means for supplying electric current to one of said circuits, and a converter connected in said other circuit to form two parallel branches of substantially equal resistance supplied by said converter with a different current of large heating capacity.

24. The combination with a main electric circuit, of a second circuit divided into a series of successive sections having normally closed circuits and each of which has a conductor common to a portion of the main circuit, means for supplying electric current to said main circuit, and a series of converters connected respectively at the centers of said sections and each dividing its section into two parallel branches of substantially equal resistance supplied by said converter with current of different character from that supplied to said main circuit and of large heating capacity.

25. The combination with a main electric circuit, of a second circuit divided into a series of successive sections of varying lengths and having normally closed circuits and each of which has a conductor common to a portion of the main circuit, means for supplying electric current to said main circuit, and a series of converters connected respectively at the centers of said sections and each dividing its section into two parallel branches of substantially equal resistance supplied by said converter with current of different character from that supplied to said main circuit and of large heating capacity.

26. The combination with a pair of electric circuits having a common conductor one of which circuits is normally open, of means for supplying electric current to the other cir-

cuit, means for supplying a different current of large heating capacity to said normally open circuit, and means for automatically closing said normally open circuit at a predetermined time.

27. The combination with a main electric circuit, of a second circuit divided into a series of successive sections each of which has a conductor common to a portion of the main circuit, means for supplying electric current to said main circuit, a series of converters connected respectively in circuit with said sections, and means for energizing said converters selectively.

28. The combination with three electric circuits two of which have conductors common to the third, of means for supplying electric current to said first two circuits and for supplying to said third circuit current of different character and large heating capacity.

29. The combination with three electric circuits two of which have conductors common to the third, of means for supplying electric current to said first two circuits and for simultaneously supplying to said third circuit current of different character and large heating capacity.

30. In an electric-railway system, the combination with a pair of electric circuits each embodying a third rail, of a third circuit formed by connecting said third rails, and means for supplying to said first two circuits electric current of one character and to the third circuit electric current of different character and large heating capacity.

31. In an electric-railway system, the combination with a pair of electric circuits each embodying a third rail, of a third circuit formed by connecting said third rails, means for supplying to said first two circuits electric current of one character, and a converter in said third circuit for supplying thereto electric current of different character and large heating capacity.

32. In an electric-railway system, the combination with a pair of electric circuits each embodying a third rail, of a third circuit formed by connecting said third rails and divided into a plurality of sections by cross-conductors, means for supplying to said first two circuits electric current of one character, and a series of converters one for each section of said third circuit for supplying to said sections electric current of a different character from that supplied to the first two circuits and of large heating capacity.

33. In an electric-railway system, the combination with three electric circuits each embodying a third rail, of two other circuits connected in parallel and formed by connecting said third rails, means for supplying to said first three circuits electric current of one character, and means for supplying to said last two circuits a transformed current of large heating capacity.

34. In an electric-railway system, the combination with three electric circuits each em-

bodying a third rail, of two other circuits connected in parallel and formed by connecting said third rails, means for supplying to said first three circuits electric current of one character, and a converter having a divided secondary connected with both of said last two circuits for supplying thereto a transformed current of large heating capacity.

35. In an electric-railway system, the combination with a working circuit and a heating-circuit having a common conductor, of an electric motor in said working circuit and in traveling electrical connection with said common conductor, and means for supplying to said circuits electric current for operating said motor and for heating said circuit.

36. The combination with a pair of electric circuits having a common conductor, of means for supplying electric current to one of said circuits and for simultaneously but intermittently supplying to the other of said circuits electric current of different character and large heating capacity.

37. In an electric-railway system, the combination with a pair of electric circuits embodying a common third rail, of means for supplying to one of said circuits an electric current of one character and for rapidly supplying to said other circuit at intervals a current of large heating capacity for quickly heating up the whole body of said third rail to a relatively high temperature.

38. In an electric-railway system, the combination with the traffic-rails thereof, of working conductors, and a source of current for heating the working conductors or portions of the same independently of the traffic-rails.

39. In an electric-railway system, the combination with traffic-rails forming one side of the working circuit, of one or more supply-conductors forming the other side of said circuit, and a source of current for heating the supply conductor or conductors or portions thereof independently of the traffic-rails.

40. In an electric-railway system, the combination with the traffic-rails thereof, of a supply-conductor therefor, and means for heating successive portions or sections of said

supply-conductor independently of the traffic-rails.

41. In an electric-railway system, a system of supply-conductors divided into closed electric circuits, and means for intermittently heating the said circuits separately from a common source of current-supply.

42. In a system of removing sleet, ice and other deposits from electric-railway conductors, a railway having a track provided with a working conductor electrically divided into sections of unequal lengths according to the relative importance of the track-sections to be cleaned, and current-supplying means connected and adapted to raise the respective temperatures of the conducting-surfaces to be cleaned to such a point that the several sections will be freed from said deposits in prearranged order in accordance with their relative importance or the requirements of traffic.

43. A system of removing sleet, ice and other vaporous deposits from electric supply-conductors, such as third rails of electric railways, comprising a source of electrical energy, a series of local circuits into which the said supply-conductors are divided, and means for passing heating-currents through said local circuits separately and intermittently or at recurring time intervals whereby the conducting-sections under treatment are caused to absorb or store part of the heat generated therein and to continue to give out a portion of the same for the purpose of removal of the deposit during the intervals between successive applications of the heating-current thereto, and whereby the total load at any one time upon the source of energy is reduced and the total load distributed over a longer time interval.

Signed at New York, in the county of New York, and State of New York, this 24th day of August, A. D. 1903.

ELIAS E. RIES.
